(57) **CLAIM**

The ornamental design for a pet adjustable sling carrier, as shown and described.

DESCRIPTION

FIG. 1 is a perspective view of a pet adjustable sling carrier showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2.

(Continued)

The broken lines in the drawings depict portions of the pet adjustable sling carrier that form no part of the claimed design.
